UNITED STATES PATENT OFFICE

JAMES M. MILLER, OF KIOWA, KANSAS

HIGHWAY MARKER

Application filed June 11, 1931. Serial No. 543,689.

This invention relates to highway markers, and more particularly to a marker which is adapted to be visible during both the day and the night.

5 An object of this invention is to provide a reflecting marker which is adapted to reflect the light of an approaching vehicle so as to illuminate the marker for determining the position of culverts, curves, bridges, or the 10 like.

Another object of this invention is to provide a marker of this kind with means whereby the indicia carried by the marker may be visible during both the day and the night, 15 the face of the marker being illuminated by the light of the approaching vehicle.

A further object of this invention is to provide a marker of this kind which may be readily and cheaply manufactured and which may 20 be mounted on any desired supporting post.

The above and various other objects and advantages of this invention will in part be described in and in part be understood from the following detailed description of the 25 present preferred embodiment, the same being illustrated in the accompanying drawings, wherein:—

Figure 1 is a detail front elevation of a device constructed according to the preferred 30 embodiment of this invention;

Figure 2 is a detail rear elevation partly broken away, and

Figure 3 is a fragmentary sectional view taken on the line 3—3 of Figure 2.

35 Referring to the drawings wherein like numerals of reference designate corresponding parts throughout the several views, the numeral 10 designates generally a supporting post in the form of a pipe or the like, which 40 is disposed in vertical position on which a highway marking member 11 is mounted. This highway marking member comprises a pair of frame sections 12 which are hinged together at one end, as at 13, and at the opposite 45 site end are provided with contacting stems

14 which are disposed within the interior of the pipe section 10 and provided with an aperture therethrough for receiving a securing pin 15 which is disposed through the pipe section 10.

50 In the present disclosure, the frame sections 12, when mounted in the pipe or support 10, form a shield, but I do not wish to be limited to this particular configuration, as the frame sections 12 may be constructed so 55 as to form any other desired configuration. The frame sections 12 are constructed of substantially U-shaped or channel construction and within the channel of the frame sections 12, there are disposed a pair of plates 16 and 17. These plates 16 and 17 are provided at the outer surface thereof with prisms so as to provide an illuminated member when light is 60 projected thereagainst. A piece of tinfoil 18 or other reflecting element is positioned 65 between the two plate members 16 and 17, this reflecting element 18 having the opposite faces thereof polished so as to reflect light through the prisms on the outer surfaces of the plates 16 and 17.

70 The outer edges of the plates 16 and 17 are preferably reduced so that the prisms will stand out from the body of the plates and from the frame sections 12. A securing band 19 is disposed about the plate members 16 75 and 17, which band is adapted to hold the two plates in tight engagement with the reflecting element 18, and this band 19 is disposed within the channel frame sections 12. Through the use of this band 19, the plate 80 sections 16 and 17 will at all times be securely held together and this band also permits the ready shipment of the plate sections without being mounted in the frame sections 12. Furthermore, the band 19 also serves to hold 85 the plate members 16 and 17 together in the event the plates are cracked or otherwise broken into relatively large pieces.

90 Preferably, the plate section 12 comprises the front of the marker herein disclosed and

the glass or transparent element is colored green or some other suitable color and is provided with blank sections 20 and 21 which are adapted to receive indicia so as to designate the highway markings and the state within which the marker is disposed. The markings or indicia 22 in the block section 20 preferably designate the state within which the marker is positioned, and the block section 21 is provided with numerals 23 designating the route number and other indicia may also be placed in this block section 21 so as to designate either a state route or a through inter-state highway which at the present time 15 is designated as a "U. S." route.

The indicia 22 and 23 may be painted or otherwise positioned on the plate section 16, so that when the plate 16 is illuminated by a headlight or other light, the indicia 22 and 20 23 will be readily visible. The plate section 17 is preferably colored red or some other suitable color so as to designate danger points, and this face portion 17 is visible on the left hand side of the road and is adapted to designate danger points in the form of curves, culverts, bridges or the like. If desired, only one of the plate sections 16 may be mounted in the frame sections 12 with the reflecting element 18 disposed on the back thereof and in 25 like manner, only one of the danger plate numbers 17 may be mounted in the frame sections 12 so as to designate only a danger point but, if desired, the two plate sections 16 and 17 may be mounted in one pair of the frame 30 sections 12 so that a vehicle approaching on the right side of the road will see the green marker on the right side and will see a red marker on the left side, there being two of these markers mounted one on each side of the 35 road.

It is obvious, from the foregoing, that a relatively simple, but at the same time practical marker has been disclosed which is adapted to take the place of the present metal 45 markers which are in use and which are only visible during the day time or at a relatively short distance at night. These markers may also take the place of the marking members which are at present in use designating curves 50 or danger points on the highways and while I have disclosed the marking members as being colored green for the front or approach side on the right side of the road and red for the danger marker, I do not wish to be limited to these particular colors as these marking members may be colored in any other suitable color or combination of colors, the colors or combinations designating various degrees 55 of danger points.

60 It is, of course, understood that various changes and modifications may be made in the details of construction and design of the above specifically described embodiment of this invention without departing from the 65 spirit thereof, such changes and modifica-

tions being restricted only by the scope of the following claims.

I claim:

1. A highway marker of the character described comprising a pair of channeled frame sections, means for hinging one end of each frame section together, complementary stem members formed with the opposite end of each frame section, means for securing said stem in a supporting member, a prismatic plate mounted in the frame sections, indicia positioned on one face of said plate, a reflecting element disposed in the frame and engaging against one face of the plate whereby to reflect light projected against the face of said plate and means disposed within the frame and engaging about the plate and element to hold the plate and element in contacting relation. 75

2. A highway marker of the character described comprising a frame, a pair of prismatic plates mounted in the frame, a reflecting element interposed between the plates, one of said plate members having a block section within the body thereof, and indicia 80 disposed within the block section. 85

3. A highway marker of the character described comprising a channelled frame, a pair of transparent members mounted in the frame, indicia on one of said members, a reflecting element interposed between said members, and a band disposed about said members. 95

4. A highway marker of the character described comprising a frame, a pair of transparent members mounted in the frame, indicia on one of said members, a reflecting element interposed between said members, and means positioned within the frame and engaging about the members to hold the members into contact with the element. 100

5. A highway marker of the character described comprising a pair of transparent members, one of said members having indicia on one face thereof, a reflecting element between the members, and a securing band extending across the outer face of each member and engaging opposed edges to hold the members in contacting relation with said element. 110

6. A highway marker of the character described comprising a pair of frame sections, means for hinging one end of said frame sections together, means for releasably securing the opposite end of said frame sections together, a pair of prismatic plate members disposed within the frame, indicia positioned on one face of one of said plates, and a reflecting element interposed between said plates and having reflecting surfaces on each side thereof whereby to reflect light projecting against each of said plates. 120

7. A highway marker of the character described comprising a pair of frame sections of U-shaped cross sectional configuration, means for hingedly securing one end of said 125 130

frame sections together, complementary stem members carried by the opposite end of said frame sections, means for securing said stem members in a support, a pair of prismatic plates mounted in the frame, indicia positioned on one face of one of said plates, a reflecting element interposed between said plates, and a band disposed about said plates and within the frame whereby to hold said plates and said reflecting element together.

10 In testimony whereof I hereunto affix my signature.

JAMES M. MILLER.
